UNITED STATES PATENT OFFICE.

JOHN P. SIMMONS, OF SAN FRANCISCO, CALIFORNIA; MERCANTILE TRUST COMPANY OF CALIFORNIA EXECUTOR OF SAID JOHN P. SIMMONS, DECEASED.

AUXILIARY AIR VALVE.

Application filed January 30, 1924. Serial No. 689,507.

To all whom it may concern:

Be it known that I, JOHN P. SIMMONS, a citizen of the United States, residing at the city and county of San Francisco, and State 5 of California, have invented new and useful Improvements in Auxiliary Air Valves, of which the following is a specification.

This invention relates to an internal combustion engine and particularly pertains to 10 an auxiliary air valve therefor.

It has been found in practice that the operation of an internal combustion engine can be more efficiently performed when a direct variation in the proportion of air in the 15 gaseous mixture is made under different speed and load conditions. With this idea in view it is the principal object of the present invention to provide means for permitting a desired volume of cold, fresh air directly 20 to the gaseous mixture formed in the carbureter and to deliver this fresh air with the gaseous vapors to the engine cylinder by means of a device which will automatically create a predetermined ratio of mixture between 25 the fresh air and the gaseous fuel, and which may be independently adjusted to meet the emergency demands for variations in the volume of fresh air required under extreme conditions.

30 The present invention contemplates the use of an auxiliary air valve communicating directly with the intake manifold of an internal combustion engine at a point between the carbureter and the engine, the said valve 35 being automatically controlled by movement of the carbureter throttle valve and being capable of independent adjustment other than the automatic control.

The invention is illustrated by way of example in the accompanying drawings, in which:

Fig. 1 is a view in side elevation showing the application of the present invention to an internal combustion engine.

45 Fig. 2 is an enlarged view in end elevation showing the operating lever of the valve and the independent adjustable means therefor.

Fig. 3 is a view in central horizontal section through the valve showing the details 50 of construction.

Referring more particularly to the drawing 10 indicates an internal combustion engine fitted with an intake manifold 11 and a carbureter 12. The carbureter is provided

with a throttle valve 13 which is controlled by a foot and hand throttle mechanism of conventional design. Mounted upon the manifold and in communication therewith is an auxiliary air valve 14 with which the present invention is particularly concerned. This valve comprises a T-shaped casing 15 forming a valve seat 16 and a manifold connection 17 disposed at right angles to the valve seat 16. The valve seat member 16 is formed with a cylindrical opening 18 extending for a distance therein. The opposite end of the member is substantially closed save for a smaller opening 19 through which shaft 20 extends. This shaft forms a part 60 of a valve member 21. The valve member is cylindrical in shape and seats within the cylindrical bore of the valve casing 16. A center bore 22 is formed in the valve member from one end and thus makes the valve 65 in the shape of an open-ended cup to which the valve shaft 20 is fastened. The side wall of this side member is formed with a port 23 which may be brought to register with the opening 17 through the manifold 70 connection.

It will be evident that by rotation of the valve the port may be brought to different degrees of opening in combination with the manifold connection 17, thus regulating 75 the volume of air which may pass in through the center bore of the valve and to the manifold. Rotation of the valve shaft 20 will bring about this result and is accomplished by movement of a valve lever 24. This lever is freely pivoted on the shaft 20 and is frictionally held against rotation therewith by a spring 25 which rests against the end face of a gear 26. This gear is fixed to the shaft 20 and is normally gripped between the lever 24 and the spring 25 so that rotation of the lever around its axis will cause a unison movement of the gear 26 and the valve. 80

The lever 24 is fitted with an arm 27 which is connected by a link 28 with the throttle lever 13 of the carbureter so that when the throttle valve is regulated by the hand or foot throttle the auxiliary air valve will also be regulated automatically and will cause increasing amounts of cold, fresh 105 air to be delivered to the manifold and there mixed with the gaseous fuel as the throttle valve is opened. In order to establish a proper ratio of action between the auxiliary air valve and the throttle valve 110

the lever extension 27 is formed with a plurality of perforations by which the connection 28 may be secured, thus making it possible to select the maximum length of stroke described by the lever and the degree of rotation of the valve.

Under certain conditions it may be desirable to temporarily provide the engine with an extremely lean mixture or at other times 10 with an unusually rich mixture. In any event this may be done in the present device by resetting the valve relative to the lever by which it is operated. This is accomplished by rotation of the valve independently of the lever. For this purpose a pinion 29 meshes with the gear 26. The pinion is carried on a shaft 30 journalled in bearings on the lever 24. A continuation of the shaft 30 forms a lever 31 by which the 20 shaft may be rotated. This lever in turn may be operated from the dash of the automobile by a connection 32.

In operation of the invention the auxiliary valve is applied to the intake manifold at some point between the carburetor and the engine. The lever extension 27 is then connected by a member 28 with the throttle and the lever extension 31 is connected with the dash operating member 32. 30. When the invention is in operation the throttle 13 will be actuated by either the hand or a foot throttle control and at the same time member 28 will act to oscillate the lever and produce rotation of the valve 35. It is to be borne in mind that the valve 21 is frictionally held against movement relative to the lever 24 by the valve spring, thus insuring that a direct movement will be imparted to the valve by actuation of 40 the member 28. In the event, however, that it is desirable to promptly or temporarily change the setting of the valve port 23, the lever extension 31 may be manipulated by the dash board control 32 to rotate the shaft 45 and the pinion 29 affixed thereto. This pinion will in turn rotate the valve gear 26 against the friction holding action of the valve spring 25 and will thus change the position of the valve member relative to 50 the entire lever structure.

It will thus be evident that by the present device an auxiliary supply of fresh, cool air may be directly injected into the manifold of the engine to mix with the gaseous fuel passing from the carburetor to the engine cylinder. This air is in a condition 55 to expand greatly when within the cylinder and will insure that a higher compression will be obtained and that the gaseous fuel mixture will be automatically varied to suit varying conditions in the engine.

While I have shown the preferred form

of my invention as now known to me, it will be understood that various changes might be made in the combination, construction and arrangement of parts by those skilled in the art, without departing from the spirit of the invention as claimed.

It will be further understood that the present invention is of great advantage not only in varying the ratio of fresh air and gaseous fuel passing to the engine cylinder, but making it possible to completely cut off the supply of gasoline to the carburetor by a manipulation of the throttle and to open the auxiliary valve to permit the cylinders to draw fresh air in directly through the manifold, this being a great saver of fuel when a vehicle is coasting down a grade and the engine is in gear, to permit the cylinder compression to be used for braking purposes.

Having thus described my invention what I claim and desire to secure by Letters Patent is:

1. An auxiliary valve member comprising a valve housing formed with an induction opening in one end thereof and an eduction port in the side thereof, a rotary valve member formed with a passageway extending in from one end communicating with a port in the side thereof, whereby air may pass in through the induction opening of the valve housing to the eduction port thereof, a valve lever frictionally held with relation to the valve and for the rotation thereof, a gear fixed to the valve and an auxiliary gear in mesh with the valve gear whereby the valve may be adjustably rotated with relation to the lever.

2. An auxiliary valve member for an internal combustion engine comprising a valve housing formed with an eduction port in the side thereof, a rotary valve member mounted in the housing and formed with an induction opening and with a port in the side thereof adapted to register with the eduction port of the housing, whereby air may pass in through the induction opening of the valve to the eduction port of the valve housing, a shaft on said valve member, a lever freely mounted thereon and adapted to be connected with the throttle control of the engine, a gear secured to said shaft contiguous to the lever, spring means frictionally holding said gear relative to the lever whereby operation of the lever will operate the valve, a pinion carried by the lever and in mesh with said gear, and means for revolving said pinion to change the position of the gear and consequently the valve relative to the lever.

JOHN P. SIMMONS.
